CLAIM

We claim the ornamental design for a tapered sleeve with
seams, as shown and described.

DESCRIPTION

FIG. 1 is a perspective view of the tapered sleeve with seams
showing our new design with the sleeve in an expanded
configuration from one end.

FIG. 2 is another perspective view thereof from an opposite
end;

FIG. 3 is a front side elevation view thereof with the sleeve
in an unexpanded configuration.

FIG. 4 is a top plan view of thereof.

FIG. 5 is a bottom plan view thereof.

FIG. 6 is a right side elevational view thereof.

FIG. 7 is a left side elevational view thereof.

FIG. 8 is a rear side elevation view thereof.

FIG. 9 is an enlarged view of a second embodiment of the
tapered sleeve with seams, taken from any area in a main
field of the design away from the seams.

FIG. 10 is a perspective view thereof with the sleeve in an
expanded configuration.

FIG. 11 is another perspective view thereof;

FIG. 12 is a front side elevation view thereof with the sleeve
in an unexpanded configuration.

FIG. 13 is a top plan view of thereof.

FIG. 14 is a bottom plan view thereof.

FIG. 15 is a right side elevational view thereof.

FIG. 16 is a left side elevational view thereof; and,

FIG. 17 is a rear side elevation view thereof.

The broken line showings of seams form no part of the
claimed design. The dash-dot line in FIG. 9 indicates a
boundary that forms no part of the claimed design.
